UNITED STATES PATENT OFFICE.

FERNAND E. D'HUMY, OF ENGLEWOOD, NEW JERSEY, ASSIGNOR TO RAMP BUILDINGS CORPORATION, OF NEW YORK, N. Y., A CORPORATION OF DELAWARE.

BUILDING.

Application filed January 25, 1921. Serial No. 439,724.

To all whom it may concern:

Be it known that I, FERNAND E. D'HUMY, a citizen of the United States, and a resident of Englewood, county of Bergen, and State of New Jersey, have invented certain new and useful improvements in Buildings (Case 4), of which the following is a specification.

This invention relates to improvements in buildings of the type in which groups of relatively staggered floors are connected by ramps to permit motor vehicles or the like to travel from the ground level to any floor of either group.

The principal object of the present invention is to provide an arrangement of groups of floors and ramps in a building of the aforesaid type which may be employed in the erection of buildings on plots of many different shapes.

In the drawings:

Fig. 1 is a horizontal sectional view, on the line I—I of Fig. 2;

Fig. 2 a vertical section on the line II—II of Fig. 1;

Fig. 3 a vertical sectional view on the line III—III of Fig. 1;

Fig. 4 a vertical section on the line IV—IV of Fig. 1;

Fig. 5 a horizontal sectional view on the line V—V of Fig. 6, showing a building similar to that illustrated in Figs. 1 to 4 provided with four series of ramps;

Fig. 6 a vertical sectional view, on the line VI—VI of Fig. 5;

Fig. 7 a vertical sectional view on the line VII—VII of Fig. 5;

Fig. 8 a vertical sectional view on the line VIII—VIII of Fig. 5;

Fig. 9 a fragmentary horizontal sectional view of a building similar to that shown in Figs. 5 to 8 illustrating a slightly modified arrangement of the ramps and storage spaces;

Fig. 10 a horizontal sectional view on the line X—X of Fig. 11 showing the invention embodied in a building erected on an L-shaped plot;

Fig. 11 a vertical sectional view, on the line XI—XI of Fig. 10; and

Fig. 12 a vertical sectional view on the line XII—XII of Fig. 10.

The building illustrated in Figs. 1 to 4 comprises four outer walls 1 and two groups of floors 4 and 5, the floors 5 being staggered

relatively to the floors 4 and being separated from the floors 4 by two dividing walls 2 and 3 extending at right angles to each other. In the construction shown in Figs. 1 to 4 the floors 5 are substantially square and the floors 4 are substantially L-shaped but it will be obvious that the shape of either group of floors may be varied, the shape and relative proportions of the floors being determined by the size and shape of the plot on which the building is erected, it being essential only that a part of at least two sides of one group of floors shall be located adjacent a part of two sides of the other group of floors.

A group of superposed and similarly inclined ramps 6 extend through the dividing wall 2. Each ramp 6 connects one of the floors 4 with the next higher one of the group of floors 5. A second series of superposed similarly inclined ramps 7 extend through the dividing wall 3. Each of the ramps 7 connects one of the floors 4 with the next lower one of the group of floors 5. The dividing walls are provided with openings for the passage of vehicles therethrough, said openings corresponding in width with the width of the ramps, each of these openings preferably extending from the top surface of one ramp to, or approximately to, the under surface of the next higher ramp of the series. With this arrangement of floors and ramps it will be obvious that a vehicle entering the building through a suitable doorway 12 giving access to the ground floor of the building, which is the lowermost floor of the group of floors 4, may travel from floor to floor by ascending the lowermost ramp 6 to the lowermost one of the floors 5, traversing said floor 5 to the lowermost one of the ramps 7, ascending the lowermost ramp 7 to the second one of the floors 4, traversing said second floor 4 around the corner of the meeting ends of the two dividing walls 2 and 3 to the second one of the ramps 6, and so on upward from floor to floor of the building. Descending vehicles traverse the floors and ramps in the reverse direction as indicated by the arrows in Fig. 1, and the ramps and connecting passages on the various floors are preferably made of sufficient width to permit vehicles forming ascending and descending lines of traffic to travel in distinct concentric paths. I have shown the two groups of ramps 6 to 110

cated closely adjacent the meeting ends of the dividing walls 2 and 3 so as to reduce the distance of travel from the lowermost to the uppermost floor of the building to a minimum, but it will be obvious that the ramps may be located at any desired point in the two walls. It is also obvious that instead of extending through the dividing walls at right angles to the walls, as shown in Figs. 1 to 4, the ramps 6 and 7 may extend diagonally through the walls, as shown in Fig. 9. It is also obvious that if desired, each set of ramps may be located entirely at one side of the adjacent dividing wall. Short side walls 8 extend through the dividing wall 2 from end to end of the ramps 6 and similar walls 9 extend through the dividing wall 3 from end to end of the ramps 7. It will be obvious, however, that guard rails may be substituted for walls 8 if desired.

The buildings illustrated in Figs. 5 to 8 is of the same construction as that illustrated in Figs. 1 to 4 with the exception that two additional series of ramps are provided. In this construction a series of superposed ramps 10 is arranged along one side of the series of ramps 6. The ramps 10 are inclined oppositely to the ramps 6, each of said ramps 10 connecting one of the floors 4 with the next lower one of the group of floors 5. A series of ramps 11 is arranged along one side of the series of ramps 7, the ramps 11 being inclined oppositely to the ramps 7. Each ramp 11 connects one of the floors 4 with the next higher one of the group of floors 5. In this construction vehicles may enter the building through the door 12 and ascend from floor to floor by means of the two sets of ramps 6 and 7 and vehicles may descend from floor to floor by means of ramps 10 and 11. With the ramps arranged as shown, it will be observed that the ascending and descending streams of traffic are concentric with each other, and that ascending and descending vehicles will travel in the same direction along the several floors of the building between the ends of the ramps communicating with the floors, thus reducing the chances of collision to a minimum. Guard walls 8 extend along longitudinal edges of the ramps 6 and 10 and guard walls 9 extend along the longitudinal edges of the ramps 7 and 11. In buildings employing four sets of ramps, outgoing vehicles may leave the building by the same door 12 by which incoming vehicles enter the building or they may leave the building by a separate door 14 conveniently located with reference to the lowermost ramp 11, as shown in Fig. 8.

The building shown in Fig. 9 is constructed in the same manner as that shown in Figs. 5 to 8 with the exception that the ramps extend diagonally through the di-

viding walls 2 and 3 and all four series of ramps are arranged in parallel vertical planes. The ramps 6 and 10 and the ramps 7 and 11 may be arranged at any desired points along the respective walls 2 and 3. 70

In Figs. 10 to 12 I have shown one way in which my invention may be embodied in a building erected upon an L-shaped plot. In the construction shown, one wing of the L-shaped floors 4 is extended beyond that side of the group of floors 5 along which the dividing wall 3 extends. The arrangement of ramps employed in this construction is the same as that employed in the building shown in Figs. 1 to 4. 75 80

The several floors of the building may be divided into storage spaces in any desired manner. I have shown these floors in the several forms of building illustrated in the drawings as divided by curbing or low partitions 13 into individual storage spaces for automobiles, there being one or more corridors or driveways on each floor communicating with the storage spaces and the ramps. In the building shown in Fig. 9 90 the partitions 13 extend diagonally from the outer walls 1 and dividing walls 2 and 3. This diagonal arrangement of the partitions facilitates driving of vehicles into and out of the storage spaces from a relatively narrow corridor and also permits economical use of the space on each floor between the ramps 10 and 11 for storage purposes. 95

As heretofore stated, in the construction shown in Figs. 1 to 8 and Figs. 10 to 12, the sets of angularly disposed ramps may be located at any desired point along the walls 2 and 3. It will be obvious that if these sets of angularly disposed ramps were located farther from the junction of the walls 2 and 3, the space at the inner corner of the floors 5 could be utilized to store vehicles. I prefer, however, to locate these sets of ramps as close as possible to the junctions of the walls 2 and 3 so as to reduce the distance of travel from top to bottom of the building to a minimum and to utilize the space at the inner corner of the floors 5 for a fire tower, stairway, elevator 110 shaft, or the like. 115

While I have only shown the invention embodied in buildings built upon square and L-shaped plots, it will be obvious that the shape of either or both groups of floors 120 may be varied as desired to afford the most economical use of floor space in buildings erected upon plots of many different shapes, it being essential only that all or a part of at least two sides of one group of floors 125 shall extend along all or a part of at least two sides of the other group of floors.

What I claim is:

1. A building having outer walls, a group of superposed angular floors overlying one 130

- part of the ground area within the outer walls, a second group of superposed floors arranged in planes intermediate the planes of the angular floors and overlying another 5 part of the ground area within the outer walls, and two series of ramps located adjacent one corner of the second group of floors and connecting each of said floors with two different angularly disposed wings 10 of two different angular floors, the ramps in each series being parallel with each other and superposed in a vertical plane.
2. A building having outer walls, a group of superposed angular floors overlying one 15 part of the ground area within the outer walls, a second group of superposed floors arranged in planes intermediate the planes of the angular floors and overlying another part of the ground area within the outer 20 walls, and ramps connecting one corner of each floor of the second group with different wings of two adjacent superposed angular floors.
3. A building comprising outer walls, a group of superposed floors within the outer walls, a second group of superposed floors staggered relatively to the floors of the first group and having different sides thereof adjoining different sides of the first group 25 of floors, two vertical series of ramps connecting the floors of the second group with the next higher floors of the first group at
- points opposite different sides of the second group of floors, and two vertical series of ramps connecting the floors of the second group with the next lower floors of the first group at points opposite different sides of the second group of floors, and all four of said series of ramps being arranged in parallel vertical planes adjacent one corner 35 of the second group of floors.
4. A building comprising outer walls, a group of superposed floors overlying a part of the ground area within the outer walls, a second group of superposed floors overlying the remaining portion of the ground area within the outer walls and located in planes intermediate the planes of the floors of the first group, a series of parallel ramps superposed in a vertical plane and connecting the floors of the second group with the next higher floors of the first group, and a second series of parallel ramps superposed in a vertical plane and connecting the floors of the second group with the next lower 45 floors of the first group, said two series of ramps being located adjacent each other and connecting the second group of floors with different angularly disposed portions of the floors of the first group adjacent one 50 corner of the second group of floors.

In testimony whereof I hereunto affix my signature.

FERNAND E. D'HUMY.
